UNITED STATES PATENT OFFICE.

JOSEPH E. MUTCHELER, OF SPARTA, MICHIGAN.

DOOR-OPERATING MEANS.

1,246,306.

Specification of Letters Patent. Patented Nov. 13, 1917.

Application filed April 27, 1917. Serial No. 164,927.

To all whom it may concern:

Be it known that I, JOSEPH E. MUTCHELER, a citizen of the United States, residing at Sparta, in the county of Kent and State of Michigan, have invented certain new and useful Improvements in Door-Operating Means, of which the following is a specification.

This invention relates to door operating means, and more particularly to means for automatically opening the door of a garage to permit the entry or exit of an automobile.

One of the main objects of the invention is to provide means of simple and durable construction for opening the door of a garage, such means being thrown into and out of operation by the approaching automobile. A further object is to provide a slidable door in connection with a rotatable drum and a cable windable on the drum and secured to the door, the drum being rotated by means of an electric motor connected thereto. A still further object is to provide simple and efficient control means for throwing the motor into and out of operation, such means being actuated by a depressible platform mounted adjacent the door opening of the garage. Further objects will appear from the detailed description.

30 In the drawings:

Figure 1 is a top plan view of an operating means constructed in accordance with my invention as applied.

Fig. 2 is a front view of the same.

35 Fig. 3 is a section taken substantially on line 3—3 of Fig. 1 with the platform raised, this view being partly diagrammatic.

Fig. 4 is a fragmentary detail sectional view through the control switch.

40 Fig. 5 is a top plan view of the control switch and door securing means actuating mechanism.

The garage indicated generally by A is provided with the door opening B which is 45 inclosed by the usual door frame having the side beams C and D. A door slide or guide beam E is secured to the front of the garage, the upper face of this beam being flush with the door plate, in the usual manner. A track 50 F is secured above the door opening and slidably receives the door G suspended therefrom by hangers H, this door being of such size as to cover the opening when in closed position.

55 The structure so far described is of stand-

ard construction and forms no part of my invention except in so far as the various elements coöperate with the opening and closing means to effect the desired result.

A drum 1 is rotatably mounted in rear of door G in a supporting frame 2 secured to the front of the garage and held rigidly in position by the lateral braces 3 and 4. A cable 5 is secured to the door G at the center of the back edge thereof, this cable being 65 also secured to the drum so as to be windable on the same thus moving the door into open position when the drum is rotated.

A pulley 6 is secured on the drum shaft and is connected by a belt 7 to a pulley 8 70 secured on the shaft 9 of an electric motor 10 mounted in front of the garage. One end of the field coils of this motor is connected by a wire 11 to a metallic sleeve 12 secured in an arm 13 which is rockably mounted at its lower end on a supporting rod 14 projecting from the front of the garage. The other end of the field coils of the motor is connected by a conductor 15 to a similar sleeve 16 secured in arm 13 in spaced relation to sleeve 12. These two sleeves are adapted to receive the contact studs or fingers 17 and 18 carried by a fixed arm or standard 19 secured to the front of the garage and spaced a short distance from arm 75 13. Finger 17 is connected by a wire 20 to the positive side of an electric battery 21, the negative side of which is connected by a wire 22 to finger 18. When the arm 13 is rocked toward arm 19 so as to electrically 80 connect the fingers 17 and 18 and sleeve 16 and 12, respectively, the motor 10 will be energized from battery 21 so as to rotate drum 1 and thus open the door.

An inclined platform 23 is rockably 95 mounted in front of the garage with its inner end closely adjacent the door plate. A supporting shaft 24 is secured to the underface of this platform adjacent the outer edge thereof. The ends of this shaft 100 are reduced to form trunnions 25 which are inserted through eyes 26 secured in blocks 27. An expansion coil spring 28 is mounted beneath platform 23 adjacent each inner corner thereof. These springs act to normally hold the inner end of the platform raised a considerable distance above the lower edge of the door-way or opening and are of such strength that, when the automobile which is to enter the garage runs 105 110

upon the platform so as to depress the same, the upper edge of the inner end of the platform will be approximately level with the lower edge of the door opening. A similar 5 platform 29 is similarly mounted inside of the garage, being normally held in raised position by the springs 30.

A control switch operating lever 31 is pivotally mounted, intermediate its ends, on a 10 rod 32 projecting from the front of the garage. The inner arm 33 of this lever extends beneath the outer platform 23, and is bent inward at right angles to provide an integral finger 34 which projects inward 15 beneath the inner platform 29, a suitable arcuate slot 35 being provided through the front of the garage to accommodate this finger. A downwardly extending stud 36 is secured on the underface of platform 23 and 20 is so positioned as to engage the upper face of arm 33 of the lever, a similar stud 37 being provided on the underface of platform 29 and positioned to engage finger 34. The outer arm 38 of lever 31 is connected 25 by a tension coil spring 39 to the arm 13 adjacent the upper end thereof. Assuming that the garage door is closed—if an automobile runs upon the outer platform 23 so as to depress the same, the inner arm of 30 lever 31 will be depressed thus rocking the arm 13 of the control switch toward the fixed arm 19 so as to energize the motor 10 and thus open the door. The motor will be thrown into operation in a similar manner 35 when an automobile which is inside of the garage is run upon the inner platform 29.

To prevent injury to the motor or the door operating means, I provide means for automatically opening the motor circuit 40 when the door has been moved into full opened position. A tripping arm 40 is rockably mounted at its lower end on a rod 41 which projects from the front of the garage. This tripping arm is connected by a short 45 cable 42 to the rockable arm 13 of the control switch adjacent the upper end thereof. A tripping finger 43 is secured in door G and projects in front of the same a sufficient distance to engage the tripping arm 40. This 50 finger is so positioned that, when the door is moved into its outermost position, the finger will engage the tripping arm so as to force the same outward thus pulling the movable arm 13 of the control switch away 55 from the fixed arm 19 and breaking the circuit of motor 10. A light tension spring 44 is secured at one end to the tripping arm 40 and at the other end to a stud 45 positioned in rear of the same and projecting 60 from the front of the garage. This tension spring serves to maintain the tripping arm 40 in a substantially vertical position so as to be engaged by finger 43. In addition, the two springs 39 and 44 provide resilient connecting means which serve as cushioning 65

elements to prevent injury or breakage of any of the motor circuit controlling mechanism.

A securing block 46 is rockably mounted at its inner end on a pin 47 projecting from 70 the front of the garage. This block is provided with an integral arm 48 which extends beneath the platform 23. This arm is bent at right angles to provide an integral finger 49 which projects through a slot 50 in 75 the front of the garage beneath the inner platform 29. The arm 48 and finger 49 are positioned to be engaged by the platform 23 or 29, respectively, when the platform is depressed so as to raise the block 46 80 against the action of the tension spring 51 secured thereto and to the finger 52 projecting from the front of the garage. A gravity block 53 is pivotally mounted on the door as at 54 and has its downward 85 movement positively limited by a stop pin 55. This block is so positioned as to engage in back of the block 46 when the door has been moved into its outermost position, thus retaining the door in open position as long 90 as the automobile remains on either one of the platforms. When the automobile has passed off of both of the platforms, the tension spring 51 acts to depress block 46 95 so as to release the gravity block 53, as indicated in Fig. 3 of the drawings, thus permitting the door to be moved into closed position.

A weight 56 is connected by a cable 57 to the front edge of the door G near the top 100 thereof, as at 58. This cable is passed over the pulley 59 mounted on the door frame to one side of the stop bar 60. When the automobile has passed off of both of the platforms 23 and 29 and the door has been released in the manner described, the weight 56 will act to return the door into closed position, in which position it will normally be maintained by this weight. 105

What I claim is:— 110

1. In door operating means, the combination with a garage having a door opening, of a slidably mounted door adapted to close said opening, a rotatable drum mounted in rear of said door, a cable secured to said door and windable on the drum so as to open the door when the drum is rotated, an electric motor for rotating said drum, driving connections between the motor and drum, a depressible platform mounted adjacent the door opening, a fixed switch arm provided with spaced contact fingers, a rockably mounted switch arm movable toward and away from said fixed arm and provided with spaced contact fingers, a 115 rockably mounted switch arm movable toward and away from said fixed arm and provided with spaced sleeves adapted to receive said fingers so as to be connected electrically thereto, a source of supply of 120

electrical energy having its opposite sides connected to the contact fingers, respectively, of the fixed switch arm, connections between the sleeves of the movable switch 5 arm and the motor, a lever pivotally mounted intermediate its ends and having one arm extending beneath said platform so as to be depressed thereby, resilient connections between the other arm of said lever and the 10 rockable switch arm, a tripping arm rockably mounted in rear of the rockable switch arm and connected thereto, and a tripping pin projecting from the door and adapted to engage said tripping arm when the door 15 is moved into open position so as to break the circuit of said motor.

2. In door operating means, the combination with a garage having a door opening, of a slidably mounted door adapted to close 20 said opening, a rotatable drum mounted in rear of said door, a cable secured to said door and windable on the drum so as to open the door when the drum is rotated, an electric motor for rotating said drum, driving 25 connections between the motor and drum, a depressible platform mounted adjacent the door opening, a fixed switch arm provided with spaced contact fingers, a rockably mounted switch arm movable toward

and away from said fixed arm and provided with spaced contact fingers, a rockably mounted switch arm movable toward and away from said fixed arm and provided with spaced sleeves adapted to receive said fingers so as to be connected electrically 30 thereto, a source of supply of electrical energy having its opposite sides connected to the contact fingers, respectively, of the fixed switch arm, connections between the sleeves of the movable switch arm and the motor, 35 a lever pivotally mounted intermediate its ends and having one arm extending beneath said platform so as to be depressed thereby, resilient connections between the other arm of said lever and the rockable switch arm, 40 a tripping arm rockably mounted in rear of the rockable switch arm and connected thereto, and a tripping pin projecting from the door and adapted to engage said tripping arm when the door is moved into open 45 position so as to break the circuit of said motor.

In testimony whereof I affix my signature in presence of two witnesses.
